(57) **CLAIM**

The ornamental design for an umbrella canopy, as shown and described.

DESCRIPTION

FIG. 1 is a top view of an ornamental design of an embodiment of an umbrella canopy comprising a first group of three contiguous double canopy panels, a first single canopy panel, a second group of three contiguous double canopy panels, and a second single canopy panel showing my new design;

FIG. 2 is a bottom view thereof;

FIG. 3 is a top view of an ornamental design of an embodiment of an umbrella canopy comprising a first group of two contiguous double canopy panels, a first group of two contiguous single canopy panels, a second group of two contiguous double canopy panels, and a second group of two contiguous single canopy panels showing my new design;

FIG. 4 is a bottom view thereof;

FIG. 5 is a top view of an ornamental design of an embodiment of an umbrella canopy comprising a first double canopy panel, a first group of three contiguous single canopy panels, a second double canopy panel, and a second group of three contiguous single canopy panels showing my new design; and,

FIG. 6 is a bottom view thereof.

The broken lines shown in FIGS. 1–6 are included for illustrative purposes only and form no part of the claimed design.
